HEATING STOVE

Maxcy Lee Brogden, Columbia, S. C.

Application December 3, 1938, Serial No. 243,838

11 Claims. (Cl. 236—96)

My invention relates to improvements in stoves.

An important object of the invention is to provide thermostatic means, in the nature of an attachment, which may be applied to a conventional heating stove, without materially altering the construction of the same, and which will serve to automatically regulate the supply of air for combustion.

A further object of the invention is to provide 10 thermostatic means of the above mentioned character, which is extremely simple in construction, and so arranged that a portion of the solid thermostatic element projects into the interior of the stove casing.

15 A further object of the invention is to provide thermostatic means for actuating the damper or air supply regulating element which is mounted upon the movable door of the stove and which will permit of the free opening or closing of the 20 door, without disturbing the operative relation between the thermostatic means and the damper.

25 A further object of the invention is to provide means whereby a part operated by the thermostatic means is separated from a part movable with the damper, when the door carrying the damper is shifted to the open position.

30 A further object of the invention is to provide an indicator for showing the relative position of the damper.

35 Other objects and advantages of the invention will be apparent during the course of the following description.

In accompanying drawings forming a part of this application and in which like numerals are 40 employed to describe like parts throughout the same:

Figure 1 is a perspective view of a stove embodying my invention.

45 Figure 2 is a central vertical longitudinal section of the same.

Figure 3 is a transverse vertical section taken on line 3—3 of Figure 2.

Figure 4 is a horizontal section taken on line 4—4 of Figure 2.

50 Figure 5 is an elevation of the inner side of the valve and cap carrying the same.

Figure 6 is a perspective view of a stove embodying a second form of the invention.

55 Figure 7 is a horizontal section taken on line 7—7 of Figure 6.

Figure 8 is a vertical section taken on line 8—8 of Figure 7.

Figure 9 is a vertical section taken on line 9—9 of Figure 6.

Figure 10 is an elevation of the inner side of the ash door, damper and associated elements.

Figure 11 is a perspective view of the damper, thermostatic element, and associated elements, and,

Figure 12 is a perspective view of the indicator disk.

The present application is a continuation in part of my pending application for Heating stove, filed December 3, 1937 Serial No. 178,004, allowed November 4, 1938, now abandoned.

In the drawings, arranged for the purpose of illustration, are shown preferred embodiments of my invention, attention being called first to Figures 1 to 5 inclusive, the numeral 5 designates the 15 casing or body portion of a heating stove, designed for burning wood, although the invention is not restricted to a wood burning stove. The casing 5 is ordinarily formed of sheet metal and is supported by legs 6 and has the usual coupling 20 or fitting 7 at its forward end, for connection with the usual pipe.

Rigidly connected with the front end of casing 5 is an air supply sleeve or tubular housing 9. This sleeve is preferably cylindrical and preferably has its longitudinal axis arranged at a slight inclination from the horizontal. The inner end of this sleeve is in free communication with the interior of the casing 5. The outer end of the sleeve 9 is adapted to be covered by a cap, closure element or door 10, hinged thereto at its top, as shown at 11, and the cap, closure element or door, is held in the closed position by a spring catch 12. This spring catch engages over a flange 13 formed upon the sleeve 9 and the cap or door 14 has a flange 14 to receive the flange 13, so that the cap or door has substantially an air-tight fit with the sleeve 9, when the cap is closed. The cap or door is provided to regulate the supply of air into the casing 5 to support combustion, and for this reason the cap or door has segmental openings, 15, adapted to register with openings 16 formed in a pivoted valve 17, arranged upon the outer side of the cap or door. By turning the valve 17 the openings 15 may be partly 45 or completely covered or closed. The stove thus described is that of the usual or conventional wood burning stove.

In accordance with my invention, I provide a vertically swinging valve, damper, or disk 18, 50 which is arranged within the sleeve 9 and is hinged to the cap or door 10, as shown at 19. The valve or damper 18 is of a suitable diameter to cover the segmental openings 15. The cap or door 10 is vertically inclined on account of 55

the inclination of the sleeve 9, and when the valve or damper 18 is released, and since it is pivotally supported at its top, it will move from the cap or door 10 to assume a vertical position and hence become spaced from the cap or door and thereby open or uncover the segmental openings 15, permitting the air to enter the casing 5 to support the combustion. However, this air will be carried to a considerable extent downwardly about the lower portion of the valve or damper 18.

The numeral 20 designates a vertically arranged housing, secured to the casing 5 by rivets or the like. This housing is arranged exteriorally of the casing 5 and above and adjacent to the sleeve 9. Mounted within the upper end of the housing 20 is a horizontal rock-shaft 21, to which is attached a solid thermostatic element 22, which is straight at low temperatures. This solid thermostatic element is in the form of a bar and embodies two metal strips having different coefficients of expansion and these metal strips are connected throughout length. When the bar thermostatic element 22 is heated, it will bend in such a manner that its lower end is moved outwardly in the direction of the arrow, so that the finger 23 carried thereby will contact with the valve 18 and move the valve or damper 18 toward the cap or door 10, to partly or wholly close the openings 15. The finger 23 has no connection with the valve or damper 18. It is thus seen that when the cap or door 10 is opened, the valve or damper 18, being unconnected with the finger 23 moves from the same, without disturbing the thermostatic element.

Adjustable means are provided to regulate the starting angular position of the bar thermostatic element 22, comprising a rod 24, having screw-threaded engagement with the housing 20 at 25. The rod is turned by a knob 26. The inner end of the rod has swiveled connection with the bar thermostatic element 22, which is effected by providing the bar 22 with an elongated slot 27, to receive the rod 24 and spacing sleeves 28 upon the rod 24, upon opposite sides of the bar 22, these sleeves being clamped to the rod. The bar thermostatic element 22 extends through a slot 29 formed in the top of the sleeve 9.

It is thus seen that I can apply my thermostatic device upon the stove without materially altering the construction of the same.

The numeral 30 designates a guard or plate which I prefer to attach to the interior of the casing 5 so that this guard will extend over the upper portion of the bore of the sleeve 9 and cover the thermostatic bar element 22 and its finger. This guard will prevent wood or the like contacting with the thermostatic element and serves to retain the sleeve 9 free and unobstructive.

In operation, when the stove is relatively cool, the valve or damper 18 is in the vertical open position, and air is drawn into the casing 5 through the openings 15 and passes about the edge of the valve 18 and enters the lower portion of the casing 5. As the combustion increases the bar thermostatic element 22 is heated and bends, moving the finger 23 toward the valve or damper 18, which in turn moves this valve or damper toward the openings 15 until the openings are covered to cut off the supply of air. The degree of heat necessary to completely close the valve or damper 18 will depend upon the starting angular position of the bar thermostatic element 22.

In Figures 6 to 12 inclusive, I have shown a second modification of the invention. In these figures, the numeral 35 designates a dwelling or room heating stove or furnace. This stove embodies an inner casing 36 and an outer jacket 37, spaced from the inner casing and affording an air chamber 36', for the circulation of air. The air enters at the bottom of this chamber and discharges from its top. The inner casing 36, at its top, discharges the product of combustion into the usual pipe 38. Numeral 39 designates the door for the introduction of fuel, such as coal, the usual grate being provided, below which is a horizontally swinging ash door 40, hinged at 41. This ash door is provided with a draft opening 42, the area of which is regulated by an adjustable valve or damper 43, adapted to be clamped in the selected adjusted position by means of a bolt 44 or the like. The draft opening 42 discharges air into the ash pit 15 below the usual grate and the opening 42 is vertical. A housing 45 is arranged upon the inner side of the horizontally swinging door 40 and is attached thereto by screws 46 or the like. This housing may be formed of sheet metal or other suitable material and has a vertically inclined side wall 47, extending inwardly in an upward direction. This side wall 47 has a draft opening 48, adapted to be covered and uncovered by a valve or damper 49, hinged at its upper 20 end, as shown at 50, with the side wall 47. The valve or damper 49 automatically gravitates to the vertical position to uncover the draft opening 48, but will cover this draft opening when swung toward the side wall 47.

The door 40 covers the opening which leads into the ash pit of the inner casing 36 and this door 40 has an outwardly projecting sleeve or tubular portion 51, having the opening 42 therein. This sleeve extends through an opening 40 formed in an outer door member 52, movable with the door 40 and serving to cover the ash pit opening in the jacket 35. The elements 52 and 40 move as a unit.

Arranged within the sleeve or tubular portion 51 is a horizontal rock-shaft 53, having a crank 54 rigidly secured thereto, carrying an adjustable bolt 55, arranged to contact with the inner side of the valve or damper 49, but free from connection therewith. The rock-shaft is journaled in openings formed in the ends of the sleeve or tubular portion 51 and this rock-shaft is connected with a second rock-shaft 56 by means of a universal joint 57. The rock-shaft 56 is journaled in a bracket 58, mounted upon the inner side of the door member 52. The rock-shaft 56 is provided at its free end with an upstanding crank 59, arranged within the space 36'. Clamped to the rock-shaft 56 adjacent to the vertical crank 59 is a horizontal crank 60, carrying a pin 61.

The numeral 62 designates a vertical supporting strip, arranged within the space 36', and mounted upon the jacket 37. This supporting strip 62 is stationary and carries a horizontal stationary bracket 63, upon which is pivoted at 64, a bar thermostatic element 65. This bar thermostatic element is made of strips of metal having different coefficients of expansion, and will bow inwardly, when heated. Rigidly attached to the lower end of the bar thermostatic element 65 is a rod 66, having a horizontal crank 67 at its free end, carrying a roller 68, arranged in advance of the upstanding crank 59 and in a position to engage therewith. At its upper end,

the thermostatic element 65 is rigidly connected with an arm 69, which is forked and has pivotal connection with a block 70, in turn having a screw-threaded opening for receiving the screw-threaded portion 71 of an adjusting rod 72. This adjusting rod is rotatably mounted within an opening formed in a bracket 73, rigidly attached to the vertical supporting strip 62. The rod 72 is provided with collars 74, clamped thereto for holding the rod 72 against longitudinal movement. The rod 72 extends to the exterior of the jacket 37 and is provided with a knob 75, for turning the same. It is thus apparent that by turning the rod 72 the starting angular position of the thermostatic element 65 may be selected and the thermostatic element will thereafter be held in the selected position.

The vertical supporting strip 62 is provided near its lower end with horizontal apertured ears 75, to receive a vertical reciprocatory indicator rod 76, provided at its lower end with a cam 77, arranged above and contacting with the pin 61. Rigidly attached to the upper end of the reciprocatory rod 76 is a connecting link 78, pivotally connected at 79 with a segmental gear 80, mounted upon a fixed pivot 81. The rod 76 is sufficiently resilient to permit the same to move laterally, due to the turning movement of the segmental gear 80. This segmental gear is in permanent mesh with a smaller gear 82, mounted upon a rock-shaft 83, supported by the strip 62. An indicator disk 84 is rigidly mounted upon the rock-shaft 83 and is provided with designations 85, indicating that the damper 49 is opened or closed, or partly so. A stationary pointer 86 is arranged to cooperate with the scale or indications 85. The indicator disk is preferably provided with a radially extending weight 87.

The operation of the second form of my invention is as follows:

With the thermostatic bar element 65 in the adjusted position shown, and the valve or damper 49 gravitates to the vertical open position, air is admitted to the ash pit, and the coal or other fuel is burning. As the stove heats up, the bar thermostatic element 65 is bowed inwardly drawing rod 66 inwardly so that roller 68 engages the upstanding crank 59 and swings it inwardly. This crank 59 then turns the rock-shaft 56 counter-clockwise, Figures 9 and 11, turning rock-shaft 53 counter-clockwise. This rock-shaft swings the crank 54 toward the valve or damper 49 and the valve or damper is moved toward the opening 48 to cover the same in whole or in part. When the damper 49 is in the vertical open position, the indicator disk 84 is positioned to bring the O adjacent to the pointer 86, but when the rock-shaft 56 turns, in the direction of the arrow, Figure 11, the pin 61 raises the cam 77 and elevates the rod 76. This turns the segmental gear 80, which turns the gear 82 in an opposite direction, and the indicator disk 84 is turned to cause the C to travel toward the pointer 86, indicating that the damper is closed in part or in whole. Particular attention is called to the fact that the vertical crank 59 contacts with the roller 68 but is not connected therewith. When it is desired to have accesss to the ash pit, the door 40 may be swung to the open position, and the crank 59 will be swung from the roller 68. The door may therefore be opened without disturbing the bar thermostatic element.

In both forms of the invention the valve or damper is carried by a hinged or pivoted cap

or door. The valve or damper is self-opening and gravitates to a vertical open position. This is the preferred arrangement but it could be opened by means of a spring instead of gravity, if desired. In both forms of the invention the bar thermostatic element serves to close the valve or damper but is not connected therewith and the cap or damper may be swung to the open position without disturbing the bar thermostatic element.

It is to be understood that the forms of my invention herewith shown and described are to be taken as preferred examples of the same and that various changes in the shape, size, and arrangement of parts may be resorted to without departing from the spirit of my invention or the scope of the subjoined claims.

Having thus described by invention, what I claim is:

1. A stove comprising a casing provided with an outlet for the products of combustion, an air inlet collar connected with the casing, a cap pivotally mounted at its upper end upon the collar and vertically inclined in an upward direction toward the casing when in the closed position, a valve arranged upon the inner side of the cap and pivotally mounted near its upper end upon the cap to move from the inclined cap by gravity, and a solid thermostatic bar element arranged in proximity to the casing and having a part to contact with the valve to swing the same toward the cap for cutting off the supply of air, the thermostatic bar element and the valve being separable so that the valve moves upwardly with the cap and with relation to the thermostatic bar element when the cap is swung upwardly.

2. A stove comprising a casing provided with an outlet for the products of combustion, an air inlet collar connected with the casing, a cap mounted upon the outer end of the collar and vertically inclined in an upward direction toward the casing, said cap having an air inlet opening, a valve arranged upon the inner side of the cap and pivotally mounted at its upper end to the cap, the valve moving toward a vertical position by the action of gravity to become spaced from the cap, and a thermostatic bar arranged adjacent to the casing and having a part extending into the collar to engage with the valve to swing the same toward the cap.

3. A stove comprising a casing provided with an outlet for the products of combustion, an air inlet collar arranged exteriorly of the casing and attached thereto, a cap mounted upon the outer end of the collar and inclined vertically in an upward direction toward the casing and having an air inlet opening, a valve arranged within the collar and upon the inner side of the cap and pivotally supported at its upper end to swing by gravity toward a vertical position to become spaced from the cap, and a thermostatic rod supported near the casing and projecting into the collar and having a part engaging the pivoted valve to swing the valve toward the inclined cap.

4. A stove comprising a casing having an outlet for products of combustion, an air inlet collar mounted upon the exterior of the casing, a cap mounted upon the outer end of the collar and inclined upwardly toward the casing, a valve pivotally supported at its top to move by gravity toward a vertical position to become spaced from the cap, a substantially vertical thermostatic bar arranged near and above the collar and having a part arranged to engage with the valve and swing the valve toward the cap, means to pivotally sup-

port the thermostatic bar at its upper end, and means to angularly adjust the bar and hold the same at the selected adjusted position.

5. A stove comprising a casing having an outlet for the products of combustion, a horizontally swinging door connected with the casing and having an air inlet, a self-opening damper pivotally mounted upon the door to control the passage of air through the opening, a rock-shaft 10 mounted upon the horizontally swinging door for moving the damper toward the closed position and having a crank, a thermostatic bar supported near the casing, a rod connected with the thermostatic bar and having a part to contact 15 with the crank and being free from connection therewith, the part being arranged upon that side of the crank which is forwardly of the direction of movement when the crank is moved inwardly due to the opening of the door so that the 20 crank and the part are separated when the door is opened.

6. A stove comprising a casing having an outlet for the products of combustion, a horizontally swinging door connected with the casing and having an air inlet, a self-opening damper mounted upon the door to control the passage of air through the opening, a generally horizontal rock-shaft mounted upon the door for moving the damper toward the closed position and having a 25 crank, a thermostatic bar supported near the casing, a rod connected with the thermostatic bar and having a part to contact with the crank and being disposed upon the outer side of the crank so that the crank is separated from the part when 30 it is moved inwardly due to the opening movement 35 of the door.

7. A stove comprising a casing having an outlet for products of combustion, a horizontally swinging door connected with the casing and having an air inlet, a damper mounted upon the door to control the passage of air through the opening, a generally horizontal rock-shaft mounted upon the door for operating the damper and having a crank, the crank moving inwardly when 40 the door is opened, a thermostatic bar mounted 45 near the casing, and a rod connected with the thermostatic bar and having a part arranged upon the outer side of the crank to contact therewith and being free from connection with the 50 crank so that the crank is separated from the part when the crank moves inwardly due to the opening of the door.

8. A stove comprising a casing having an outlet for products of combustion, a horizontally swinging door connected with the casing and 55

having an air inlet opening, a movable damper mounted upon the door to control the passage of air through the opening, a generally horizontal rock-shaft mounted upon the door and serving to operate the damper, said rock-shaft having a 5 generally vertical crank, a thermostatic bar supported near the casing and provided with a part arranged to contact with the outer side of the crank, the crank moving inwardly and separated from the part by the opening movement of the 10 door, and an indicator device operated by the rock-shaft.

9. A stove comprising a casing having an outlet for the products of combustion, a horizontally swinging door for the casing having an air inlet 15 opening, a movable damper for controlling the passage of air through the opening, a generally horizontal rock-shaft mounted upon the door and serving to move the damper, a generally vertical thermostatic bar arranged near the casing, a 20 rod connected with the thermostatic bar, means effecting an operative connection between the rod and rock-shaft, means to pivotally support the thermostatic bar, and means to angularly adjust the thermostatic bar. 25

10. A stove comprising a casing having an outlet for products of combustion, a horizontally swinging door having an air inlet opening, a damper to control the passage of air through the opening, a rock-shaft mounted upon the door and 30 serving to operate the damper, a thermostatic bar supported separate from the door and arranged near the casing, means operated by the thermostatic bar to turn the rock-shaft, an indicator, and means operated by the rock-shaft to actuate 35 the indicator.

11. A stove comprising a casing having an outlet for the products of combustion, an air inlet collar mounted upon the exterior of the casing, a member carried by the collar and extending across 40 the bore of the collar, said member having an air inlet opening, said member being vertically inclined in an upward direction toward the casing, a valve arranged within the collar upon the inner 45 side of the member and pivotally mounted at its upper end upon the member, the valve moving inwardly to a vertical position by the action of gravity to become spaced from the member to uncover the opening, a thermostatic bar arranged adjacent to the casing, and a device operated by 50 the thermostatic bar, said device extending into the collar behind the valve and contacting with the inner face of the valve to swing the same outwardly toward said member.

MAXCY LEE BROGDEN.
